UNITED STATES PATENT OFFICE

WILLIAM DOHERTY, OF WEST PHILADELPHIA, PENNSYLVANIA

AUTOMATIC WATER-COOLED REFRIGERATOR

Application filed November 19, 1927. Serial No. 234,476.

The present invention relates to water cooled refrigerators and has for its object to provide a refrigerator in which the cooling thereof is effected by the flow of water through a portion thereof.

A further object is to so combine the flow of water through the refrigerator and the current of air circulated therethrough that the poisons and germs of decay will be withdrawn from the food compartments and will be eliminated from the interior of the refrigerator.

A further object is to provide novel and effective mechanisms whereby the above results are accomplished.

Other objects and advantages will appear from the subjoined specification and will be set forth in the appended claim, and I do not wish to be limited in the scope of my invention except as I shall be limited by said claim.

In the drawings:—

Figure 1 is a vertical section on line 1—1 of Figure 2, showing the compartments of the refrigerator and the water chamber connected therewith.

Figure 2 is a horizontal section on line 2—2 of Figure 1 looking in the direction of the arrows.

Figure 3 is a section on line 3—3 looking in the direction of the arrows and showing the mechanism for regulating the flow of water through the refrigerator in plan view.

Referring to the drawings in detail, the same reference characters designating the same parts in all views of the drawings, 10 designates the casing of a refrigerator which is spaced from the floor by suitable supports 11, which are concealed by an apron 12, secured to the lower portion of the refrigerator skirting the same to a distance therebelow so as to substantially contact with the floor. The refrigerator may be divided into any number of compartments as shown in the present drawings. It is divided into compartments A and B by the vertical partition 13. The front of the ice box may be provided with suitable doors 14 and 15 and with latches 16 for holding the doors closed. The compartments may be divided transversely

by grids 17, removably secured to the walls as by being provided with downwardly bent side flanges 18 adapted to hook into supporting brackets 19 secured to the sides of the refrigerator. The two compartments A and B communicate at their lower ends with two additional compartments C and D arranged one behind the other. The compartment C may be used to store food or anything that is desired to be preserved. The compartment D constitutes the water chamber and is provided with inlet and outlet pipes 20 and 21 in communication therewith having portions thereof at 22 and 23 respectively extending above the bottom of the refrigerator. The flow of water into the compartment D is regulated through a float controlled valve 24, which may be in the nature of a hollow ball adapted to fit in the upper end of the pipe extension 22, and which is mounted on a weighted lever 25, pivoted at 26 to a suitable support 27, which is secured to the bottom of the compartment, the lever 25 being connected with a float lever 28 pivoted to a rod 29, supported in the compartment intermediate of its ends and connected with the lever 25 through a link 30 pivotally secured to the adjacent ends of said levers. The opposite end of the lever 28 is provided with the usual float 31 secured thereto in a well known manner. The outlet pipe is controlled through a spherical valve member 32 manually controlled through the bell crank lever 33, the handle 34 and the link 35 connecting the handle with one arm of the bell crank lever, the other arm being connected to the valve through the rod 36.

An overflow pipe 37 is provided within the compartment D having communication with the outlet pipe 21 at 38, the upper end of the pipe 37 being adjusted to the desired level of the water within the compartment and further pipe 39 is provided having communication with the inlet pipe at 40 and having its discharge end 41 located within the upper end of the pipe 37 whereby a constant flow of water may be maintained as well as maintaining the level of water within the compartment.

In the top of the refrigerator, I position an electric fan as shown at 42 which is de-

signed to maintain a circulation of air within the compartments and through the foods and other substance contained therein. The air passing through the foodstuffs takes up the germs and poisonous matters and carries them with the flow of current into contact with the water within the compartment B whereby the poisons and germs are taken up and are from time to time carried off through the overflow or drain pipe 37. The air will come into contact with the water, will give up its heat and become cooled. When the water has been discharged by manual operation of the handle 34, the compartment will automatically be filled through the inlet pipe 20 by reason of the fact that when the water level falls below a certain predetermined height, the valve 24 will be raised through the instrumentality of the float 31 and the lever connections therewith. When the water rises above the predetermined level, the excess water will flow through the drain pipe bringing the level to its proper height within the compartment.

25 Having described my invention, what I claim is:—

In a refrigerator, a casing, a water inlet pipe extending through the bottom of said casing, a valve controlling the inlet pipe, a support secured to and rising from the bottom, a weighted lever pivoted adjacent one end to the support and carrying the valve, a float actuated lever linked at one end to the adjacent end of the valve carrying lever and having pivotal connection in said casing, an outlet pipe extending through the bottom of the casing, a manually operated valve for controlling the outlet pipe, a drain pipe in communication with the outlet pipe and rising therefrom to a plane above the top thereof, and means of communication between the inlet pipe and the outlet pipe and through the instrumentality of the drain pipe.

40 In testimony whereof I affix my signature.
45 WILLIAM DOHERTY.
